TYPEWRITING MACHINE

Russell G. Thompson, West Hartford, Conn., assignor to Underwood Elliott Fisher Company, New York, N. Y., a corporation of Delaware

Application February 20, 1937, Serial No. 126,903

5 Claims. (Cl. 197—17)

This invention relates to typewriting machines and more particularly to locking mechanism therefor. It has special application to power-driven typewriters which have a multiplicity of 5 key-selective power-operated type actions, an automatic line-end margin stop and a key-selective power-driven carriage-return mechanism.

It is an object of the present invention to provide a simple, inexpensive, compact and reliably 10 operative locking mechanism of the crowding-lock type by which not only are the actuators for the remaining type-action-selecting keys locked against operation when the actuator for one type action is in operation, but the carriage-return 15 actuator is cooperatively associated with the crowding-lock units so as to be prevented from operation when any type action is in printing position, and furthermore, the operation of returning the carriage locks the entire type-action-selecting keyboard until the carriage has been 20 returned to its home position.

It is a further object of the invention to include in cooperation with such a crowding-lock mechanism a simple means for locking the type-action-selecting keys when the line-end margin 25 has been reached by the traversing carriage.

The invention consists of a row of shiftable units confined between limiting stops at each end with a predetermined amount of looseness or 30 play, and blades on the various type-action actuators and a blade under control of the carriage-return-mechanism actuator and also under control of cooperative line-end margin stops, any 35 one of which blades is adapted to be entered between the shiftable units to close up the row and prevent the introduction of any other blade until the first entered blade has been removed. By this means a key, selected for the purpose of causing a type action, may be operated to engage 40 an actuator for the particular type action with a driving unit, and this actuator will enter its blade between the shiftable units and prevent operation of any other type-action-selecting key, or the carriage-return key, to move its actuator 45 into engagement with the driving unit. When, in the course of the letter-feed traverse of the carriage, its line-end margin stop engages a cooperative stop mounted on the frame a locking blade common to the line-end margin and the 50 carriage-return enters between the units and the entire type-action-selecting keyboard is locked until the margin release key is manually operated to disengage the cooperative stops which withdraws the blade. After the typing of the last 55 letter of a line the carriage-return key may be

depressed to cause engagement of its actuator with the power-drive unit which reintroduces the blade constituting the line-end margin lock and locks the entire type-action-selecting keyboard during the carriage-return movement of which a 5 preliminary step is the line-spacing of the roller platen on the traversing carriage.

In the accompanying drawings:

Fig. 1 is a side view of a power-driven typewriter with a part of the frame and top cover removed to more clearly show the interior construction. Also for the sake of clearness various parts unnecessary to an understanding of the present invention have been omitted.

Fig. 2 is a top plan view partly in horizontal 15 section of the machine shown in Fig. 1.

Fig. 3 is a view in perspective taken from the rear of the machine with part of the frame removed and the construction generally skeletonized to more clearly show the invention.

Fig. 4 is a view in perspective of a part of the crowding lock mechanism and actuating devices for one of the blades.

Fig. 5 is a detail view in end elevation of a part of the line-spacing devices.

Fig. 6 is a sectional view taken on the line 25 6—6 of Fig. 1.

Referring now more particularly to the drawings, a typewriter frame is indicated at 10 having side walls 11 and 12 and a rear wall 13. The 30 side walls 11 and 12 are joined by a bar or backbone 14 reinforcing the frame and for supporting and guiding various actuating devices later to be described. An anchor bar 15 also connects the side walls 11 and 12 and a comb-slotted bar 16 35 extends between the side walls of the machine and serves as a support for the shiftable units of the crowding lock device. A paper carriage is indicated at C suitably mounted on the frame for the usual letter-feeding movement under the influence of a conventional spring motor (not shown) controlled by any suitable escapement mechanism as indicated by the dot-and-dash lines in Fig. 1 at E. The carriage has opposite end plates 20 rotatably supporting a roller platen 21 40 and also supporting a margin stop rack 22 and a carriage rail 23 mounted in anti-friction bearings in a track 24 supported in the conventional way by a case-shift or balancing frame, the construction or operation of which frame does not 45 enter into the present invention. Also supported between the end plates of the carriage is a rail 25 the rear edge of which runs against a face plate 26 of a center tie member 27 suitably supported by the frame of the machine.

55

A power-drive unit is shown at 30. This unit is preferably in the form of a toothed or fluted roller mounted in suitable bearings in the side walls 11 and 12. This roller is adapted to be continuously rotated by an electric motor. For transient engagement with the driving unit 30 a multiplicity of actuators 31 are respectively mounted in slots 32 of the backbone 14 and guided in these slots by a pin 33 passing through the backbone 14 and common to all of the actuators 31. These actuators are slotted as shown at 34 to receive the pin 33 and each actuator carries a pivoted pawl 35 having teeth 36 adapted to engage the teeth of roller 30 when any actuator 31 is moved around the pivot pin 33 by any one of a plurality of dogs 37. These dogs project respectively into the slots 32 of the backbone 14 in position to contact the actuators 31 and swing the pawls 35 into engagement with the driving unit. Each dog is pivoted on the end of a key lever 40, all of the key levers being of substantially uniform shape and all of them being pivoted on a rod 41 which passes through the backbone 14 in parallelism with the rod 33. Upper and lower stops 42 and 43 limit the range of movement of the key levers and return springs 44 anchored to a plate 45 on bar 15 serve to restore the key levers against the upper stops 42 when keys 46 are released after depression. A key 47 tops a carriage-return lever 48 which is fulcrumed on the rod 41 and is provided with one of the dogs 37 which is adapted to move an actuator 50 corresponding in design to the actuators 31 except that it has an upper extension 51 pivotally connected to a lever 52. This lever is pivoted at 53 to the frame of the machine and its opposite end 54 is pivoted at 55 to a toggle link 56 which is tied to a friction clutch plate 57 by connector means 58. Each of the actuators 31 adapted to be selected by keys 46 have their upper ends connected by links 60 to the different type actions in conventional arrangement in the top plate of the machine.

Each of the actuators 31 has a downwardly extending arm 61 which has a laterally extending lug 62 forming an offset part of a horizontally extending blade 63 at the bottom of the actuator. At the extreme forward ends of the blades 63 return springs 64 connect the actuators with an anchor plate 65 secured to the under face of the backbone 14.

A crowding lock section, best shown in Figs. 1, 2 and 4, comprises the bar 16 extending between the side plates of the frame and a row of relatively shiftable units 67 positioned in a shoddered portion 68 of said bar, which shoulder is formed in part by a plate 70 secured to the under face of the bar and extending forwardly. The bar and its attached plate 70 are comb-slotted as indicated at 71 to constantly receive the lugs 62 of the actuators and guide the blades in the crowding lock section. The shiftable units 67 are preferably in the form of uniformly sized balls which rest in the shoulder 68 on platforms 72 provided by the forwardly extending slotted portion of plate 70. The bar 16 is longitudinally milled on its under side toward the front to provide a groove for the reception of the balls 67 and lips 73 of the bar which are defined by the longitudinal milling and comb-slotted operations overhang the balls and in conjunction with the platforms 68 retain them in position. End stops 75 and 76 loosely confine the shiftable units, and end stop 75 is in the form of an adjustable

eccentric by which the amount of looseness or play in the entire row of units may be determined. This amount of play is fixed as the thickness dimension of any one of the blades 63 so that as one blade is entered between two adjacent shiftable units the units are tightly packed between the limiting stops at both ends. Thus all other blades are held against entry and all of the actuators are held against movement by their respective keys until the blade previously entered has been withdrawn.

When any type-action-selective key 46 is depressed its associated dog 37 is moved to engage one of the actuators 31 and swing it around pivot pin 33 thus engaging its pawl 35 with the driving unit 30. The swinging movement of the actuator introduces a horizontal part of blade 63 between adjacent balls 67. The subsequent downward movement of the actuator introduces the lug 62 between the adjacent balls and no other actuator blade may be introduced to the lock section until the first moved actuator has returned to its upper position.

At one end the bar 16 is slotted from the rear as indicated at 80 to receive a blade 81 which is adapted to function both by the engagement of the line-end margin stops and the operation of actuator 50 when the latter is selected by depression of the carriage-return key. Obviously when the blade 81 is in position between the end stop 75 and the next positioned ball 67 of the crowding lock, no type action may be set in operation as all of the blades 63 of actuators 31 are held against movement.

The devices for controlling movements of the blade 81 will now be described. They involve, first, a conventional line-end margin stop 82 adjustably fixed on the carriage stop rack 22, and a cooperating stop in the form of a lug 83 forwardly projecting into the path of the stop 82 from a bar 84 pivotally supported at one end on an arm 85 and at the other end on a link 86 which in turn is pivotally supported on an arm 87. The arms 85 and 87 are fixed on the upper ends of rock shafts 88 and 89 respectively and these shafts are suitably journaled in lugs 90 and 91 projecting forwardly from the rear wall 13 of the frame. As the carriage moves in its letter feed direction from right to left the stop 82 on the carriage bar 22 engages the lug 83 and shifts link 84 from right to left. By arm 85 the rock shaft 88 is rotated to swing a fixed arm 92 and through a connector 93 swing a U-shaped lever 94 around a stud 95 which is fixed in a bracket 96 attached to the rear wall 13 of the frame. The movement is in a direction to push forwardly a rod 78 pivoted to the end of lever 94 at 79. The forward end of rod 78 is pivotally secured to a rocker frame 97 which is mounted on a stud 98 projecting from a boss 99 on the side wall 12 of the frame. The rocker frame 97 has an angle bracket 100 secured to the under side thereof and pivotally connected by a link 101 to the upper end 102 of a lever 103. This lever is pivoted on a stud 104 which passes through the bell crank lever 105 and into a boss 106 of a bar 107 secured to the side walls of the frame and having a laterally extending arm 108 for a purpose later to be described.

The lower end of lever 103 has a rearwardly extending portion with an inturned flange 110. A set screw 111 passes forwardly through this flange and bears against a lip 112 at the lower end of an arm 113 of bell crank lever 105. At the extreme lower end of arm 113 the blade 81

is pivoted and normally held retracted from the units of the crowding lock by a spring 114.

When the rod 78 is advanced forwardly as stated and rocks the rocker frame 97 the upper end 5 of lever 103 is moved rearwardly advancing set screw 111 to move the arm 113 of bell crank lever 105 forwardly, which advances the blade 81 into position between the end stop 75 and the next adjacent ball 67 of the crowding lock mechanism. It will be seen, therefore, that engagement 10 of stop 82 of the carriage with lug 83 causes all the type-action-selecting keys to be locked in the position shown in Fig. 1. For the reason that no blade 63 of any actuator can be moved rearwardly around the pivot pin 33 and inasmuch as the dogs 37 substantially abut their respective actuators, no appreciable, or actuator-engaging, movement of the key levers can be had.

A margin release key 120 is shown depressed in 20 Fig. 1 of the drawings. The key lever 121 for this key is substantially in the form of the other key levers and is pivoted in like manner on the pin 41. However, this key lever 121 has a rearward extension 122 the far end of which is provided with two slots 123 and 124 substantially concentric with the pivot 41. In the slot 124 is a pin 125 connecting the end of the margin release lever with a link 126 which in turn connects with a bell crank lever 127 pivotally mounted on the 30 end of extension 108 of bar 107 and therefore pivotally supported by the frame of the machine. The other end of the bell crank lever 127 is connected by a rod 128 with a rock arm 129 fixed on the shaft 89.

35 When the margin release key is depressed the rear end of the key lever 121 is lifted raising the link 128 and swinging the bell crank lever 127 to pull the rod 128 forwardly in a direction diagonal of the machine, as shown in Fig. 2 of the drawings. The rocking of the arm 129 and shaft 89 in the consequent direction moves rock arm 87 at the top of the shaft 89 to swing the link 84 rearward on the pivot provided by its connection with the forward end of arm 85. Thus the lug 83 is released from engagement with the stop 82 and immediately passed beyond said stop by return spring 130 which pulls lever 94 back to normal position. The restoring of lever 94 to normal position moves rocker frame 97 in the reverse direction and through the connections 50 just described removes the set screw 111 from bell crank lever 105 allowing spring 114 to retract the blade 81. To insure the retraction of the blade bell-crank lever 105 is positively rocked by the key lever 121 through the extension 122 by picking up a stud 133 in the slot 123 which stud is on a link 134 pivotally connected to the bell-crank 105.

After additional typing, if desired, the carriage-return key 47 is depressed causing engagement of the pawl 35 of actuator 50 with the teeth of driving unit 30. There is a consequent downward movement of the actuator 50 which by reason of its connection with lever 52 pulls down the end of 65 the lever until it engages a lip 131 on the rocker frame 97. This rocks the frame in the same manner that it was rocked by advancing the rod 78 under the influence of the margin release stops and through the same links and levers the 70 blade 81 is advanced into position between the end stop 75 and the next adjacent ball 67 of the crowding lock mechanism. Pulling down the end of lever 52 as described also straightens a substantial toggle, constituted by the other end 54 of lever 52 and link 56, until spring 54 takes

effect on the other side of pivot pin 55. This toggle action forces the clutch plate 57 outwardly around suitable fulcrums which cause a friction coupling of tape drum 135 with a shaft 136 which preferably is an extension of the continuously rotating power driver 30. The drum 135 rotates to wind up a tape 137 which passes around an idler 138 mounted on the frame and around another idler 139 suitably mounted on the frame and the end of the tape is connected 10 to a line-spacing lever 140 at 141.

Winding of the tape 137 on to the drum 135 first pulls down the line-space lever 140 causing a pawl P to engage with line-spacing ratchet wheel 142 of a conventional platen rotating mechanism 15 to line-space the platen a required amount. The lever 140 is guided in a slot 143 in a bracket 144 which also carries the idler 139. When the line-space lever has reached the limit of its downward movement continued winding of the tape returns 20 the carriage until its other margin stop 146 engages lug 83 of bar 84. This swings arm 85 and shaft 88 in the reverse direction and acts through the medium of parts 92, 93, 94 and 78 to reverse the direction of swinging movement of rocker 25 frame 97, thus releasing lever 102 and allowing spring 114 to withdraw blade 81 from its position between the locking units. Also effected by this reverse movement of rocker frame 97 is the breaking of the toggle 54—56 by the upward 30 movement of lip 131 which raises one end of lever 52 to move the pivotal connection 55 past the center line of spring 56 which latter collapses the toggle disconnecting the friction clutch and the carriage is again ready for normal character-writing operation. 35

If it is not desired to write beyond the line-end margin stop, the carriage return key may be depressed without first operating the margin release lever, thus setting the friction clutch in operation 40 as heretofore described and returning the carriage directly from its position of engagement of stop 82 with lug 83 to its position to begin another line of writing.

Adjustable knock-off screws 147 are threaded 45 in the bar 16 in position to engage cam faces 148 of the respective actuators 31 and disengage them from the driving unit by throwing or swinging their lower ends forwardly around the pin 33 against a stop face of the backbone 14. When 50 thus released from the driving unit each actuator is returned upwardly by its spring 64 and by conventional return springs for the connected type action.

A universal bar 150 underlies the lock section 55 and is adapted to be actuated by each actuator as it is thrown down by the power drive unit 30. The bar 150 is mounted on a rock shaft 151 suitably journaled in the machine frame and this shaft has connections for operating the escape- 60 ment E as each actuator is moved downwardly between the balls 67 and through the slots 71 in plate 70 of the locking unit.

What is claimed is:

1. In a power-driven typewriter having a 65 frame, a carriage adapted to traverse the frame, a multiplicity of type actions, a carriage-return mechanism, a driving unit, actuators transiently engageable with the driving unit to operate the type actions and the carriage-return mechanism, 70 and keys for causing said engagement; the combination of a locking mechanism for the said keys, comprising a row of relatively shiftable units loosely confined within limits, and blades controlled respectively by the said actuators for the 75

type actions and the carriage-return mechanism, any one of which blades is adapted to enter between the limits and take up the looseness of the units to thereby prevent the introduction of more than one blade at a time.

2. In a power-driven typewriter having a frame, a carriage adapted to traverse the frame, a multiplicity of type actions, a carriage-return mechanism, a driving unit, actuators transiently engageable with the driving unit to operate the type actions and the carriage-return mechanism, and keys for causing said engagement; the combination of a locking mechanism for said keys, comprising a row of relatively shiftable units 10 loosely confined within limits, a blade and operating connections controlled by the actuator for the carriage-return mechanism, and a blade on each of the actuators for the type actions, any one of said blades, when its actuator is engaged with the driving unit, being adapted to enter between the limits and shift the units to take up the looseness of the units and thereby prevent the introduction of more than one blade at a time.

3. In a power-driven typewriter having a frame, a carriage adapted to traverse the frame, a multiplicity of type actions, a carriage-return mechanism, a driving unit, actuators transiently engageable with the driving unit to operate the type actions and the carriage-return mechanism, and keys for causing said engagement; the combination of a locking mechanism for said keys, comprising a row of relatively shiftable units 25 loosely confined within limits, a blade and operating connections controlled by the actuator for the carriage-return mechanism, a blade on each of the actuators for the type actions, any one of said blades, when its actuator is engaged with the driving unit, being adapted to enter between the limits and shift the units to take up the looseness 30 of the units and thereby prevent the introduction of more than one blade at a time, cooperative line-end margin stops on the carriage and frame, and connections between the frame stop and the blade controlled by the carriage-return actuator 35 for causing said blade to enter between said limits when the frame stop is engaged by the carriage stop.

4. In a power-driven typewriter having a frame, a carriage adapted to traverse the frame, a multiplicity of type actions, a carriage-return mechanism, a driving unit, actuators transiently engageable with the driving unit to operate the type actions and the carriage-return

mechanism, and keys for causing said engagement; the combination of a locking mechanism for said keys, comprising a row of relatively shiftable units 5 loosely confined within limits, a blade and operating connections controlled by the actuator for the carriage-return mechanism, a blade on each of the actuators for the type actions, any one of said blades, when its actuator is engaged with the driving unit, being adapted to enter between the limits and shift the units 10 to take up the looseness of the units and thereby prevent the introduction of more than one blade at a time, cooperative line-end margin stops on the carriage and frame, connections between the frame stop and the blade controlled by the carriage-return actuator for causing said blade to enter between said limits when the frame stop is engaged by the carriage stop, and a margin release key and connections for disengaging said 15 stops and simultaneously withdrawing the last 20 mentioned blade.

5. In a power-driven typewriter having a frame, a carriage adapted to traverse the frame, a multiplicity of type actions, a carriage return mechanism, a driving unit, actuators transiently engageable with the driving unit to operate the type actions and the carriage-return mechanism, and keys for causing said engagement; the combination of a locking mechanism for said keys, comprising a row of relatively shiftable 25 units loosely confined within limits, a blade and operating connections controlled by the actuator for the carriage-return mechanism, a blade on each of the actuators for the type actions, any one of said blades, when its actuator is engaged 30 with the driving unit, being adapted to enter between the limits to take up the looseness of the units and thereby prevent the introduction of more than one blade at a time, a line-spacing mechanism operative as a preliminary to the 35 carriage-return operation upon the establishment of engagement between the carriage-return actuator and the driving unit, cooperative line-end margin stops on the carriage and frame, connections between the frame stop and the 40 blade controlled by the carriage-return actuator for causing said blade to enter between said limits when the frame stop is engaged by the cooperative stop on the carriage, and a margin release key and connections for disengaging said 45 stops and simultaneously withdrawing the last 50 mentioned blade.

RUSSELL G. THOMPSON.
